UNITED STATES PATENT OFFICE.

CONRAD KNOTH, OF HILLSIDE, NEW JERSEY, ASSIGNOR TO GENERAL MOTORS CORPORATION, OF DETROIT, MICHIGAN, A CORPORATION OF DELAWARE.

APPARATUS FOR FEEDING ARTICLES.

Application filed June 16, 1923. Serial No. 645,783.

This invention relates to feeding apparatus and is herein shown as embodied in an apparatus for feeding hollow rollers that go into roller bearings.

- 5 In the manufacture of hollow rollers for bearings, it has been the practice, prior to this invention, to harden the rollers by passing them slowly through a furnace and quenching them in a bath of cooling liquid.
- 10 Upon such prior apparatus, groups of rollers are laid by hand, side by side, on cast iron frames and these frames with the rollers are slid down an inclined track in the furnace while the rollers are subjected to direct contact with the hot gases heating the furnace. As the rollers leave the end of the furnace, they leave the frames and drop sidewise into the liquid. The hot frames then have to be removed by tongs and allowed 20 to cool before being loaded again. This kind of apparatus requires several operators, some to load the rollers, and some to remove the frames; the rollers are exposed to the impurities in the products of combustion 25 and are not quenched uniformly because the air imprisoned in the rollers when they drop sidewise into the liquid, retards the entry of the liquid into the inside of the rollers. The inclination of the track necessitates the raising of one end of the furnace above the other 30 and the workmen, at the high end, are obliged to work in an awkward position on a raised platform.

It is accordingly one of the objects of this 35 invention to provide a feeding apparatus for articles which will require less labor and attention and perform better work. In the illustrated construction, no loading frames are used; the rollers are fed from a hopper 40 and pushed through the furnace in a stream in end-to-end relation. To shield the rollers from the flames, they are directed through hollow tubes traversing the furnace and then to quench them quickly, they 45 are made to drop endwise into the cooling bath, the liquid thus entering the center of each roller as fast as it rises on the outside.

To these ends and also to improve generally upon apparatus of this character, the 50 invention also includes other features hereinafter described and claimed and shown in the accompanying drawings, in which:

Figure 1 is an end elevation of the apparatus.

55 Figure 2 is a right hand side elevation of

Figure 1 with a portion of the furnace shown in section.

Figure 3 is a section on the line 3—3 of Figure 1.

Figure 4 is a detail view of one of the feed rollers.

Figure 5 is a vertical longitudinal section through the furnace and

Figure 6 is a plan view of the furnace with the upper half removed.

The work pieces to be treated, in this case hollow cylindrical rollers made of spirally wound steel ribbons, are placed in a hopper and picked up and fed in end-to-end relation through hollow tubes and dropped into a second set of tubes through which their speed is regulated by feed rollers, the rollers then passing very slowly through tubes traversing a furnace after which they are quenched in a bath of liquid. The numeral 10 designates a hopper having inclined sides 12, the lower edges of which are flanged as at 14 and secured to the outer pair of a series of angle irons 16 which form an inclined bottom for the hopper. The angle irons 16 are arranged with their apexes upwardly and are slightly spaced apart to form slots 70 extending longitudinally through the bottom of the hopper. Thus a series of upwardly open channels are formed which cause the rollers to align themselves by gravity at the bottoms of the channels. The work pieces are then picked up and fed in end-to-end relation by series of feeding fingers or pushers 18, projecting through the 75 slots in the hopper and secured to bars 20 which are guided between the flanges of angle irons 22 and 24. The bars are connected by two endless sprocket chains 26 which pass around sprocket wheels 28 on 80 the driven shaft 30 and around sprocket wheels 34 on a shaft 32, journaled in the frame of the hopper. 85

To prevent any breakage of the parts in case the rollers become jammed, the shaft 30 is frictionally driven so that it can slip. A disc 38 is fixed to the shaft 30 and, spaced from this disc, is a second disc 40 which is pressed towards the first disc by springs 42 interposed between the first disc and the 90 heads of a series of bolts fixed to the second disc. A sprocket ring 44 is thus yieldingly held between the two discs and is driven by a sprocket chain 46 running around the sprocket wheel 48, fixed to a drive shaft 50 95

journaled on the frame. It should be noted that the bars 20 and feeding fingers 18 are guided at a slight angle to the course of the channels in the hopper so that the feeding fingers of each set gradually leave the channels and transfer the feeding action to the next succeeding set. As the rollers slide upwardly in the channels, they enter a series of tubes 52 which in effect form continuations of the channels and extend upwardly to a bracket 54 by which they are attached to a second set of tube sections 60 and 62. As the rollers emerge from the open ends of the tubes 52 they drop into the open or cut-away portions 58 of the tube sections 60. They are fed from the tubes 52 faster than they can be carried away by the tube sections 60, the excess rollers dropping into a pan 56 by which they are directed back into the hopper again.

10 The tube sections 60 and 62 form an inclined conduit or guide through which the rollers tend to feed themselves by gravity. The sections 62 are bent in a gradual curve and are joined by horizontal tube sections 25 64 and 66 to a series of tubes 68 extending into the fire box of the furnace 70. The rollers are fed very slowly through the furnace and to regulate their speed, feeding discs 72 and 74 are provided. The feeding discs 72 of one set are fixed to a horizontal shaft 76 which is movably mounted and the discs 74 of the other set are mounted on a shaft 78 journaled in a bracket on the frame. The shaft 78 is driven at slow speed by a worm wheel 80 at one end, engaged by the worm 82. The shaft 76 is driven at the same speed and in the opposite direction from the shaft 78 through the medium of sprocket wheels 84 and 86 near the ends of 30 the respective shafts and a chain directed about the sprocket wheels and the large sprocket wheel 88 in the manner indicated in dotted lines in Figure 2.

35 The tube sections 64 are slotted above and below (see Figure 6) opposite the feed discs so that the latter will have access to the rollers being fed. The upper set of feed discs is yieldingly pressed towards the other set, the shaft 76 being mounted in lever arms 90 pivoted at 92 to brackets on the frame and 40 pressed downwardly by weights 96 attached to the lower ends of bars 94 that are pivotally hung in the ends of the lever arms 90. As indicated in Figure 4, the discs 72 are 45 provided with a yieldable mounting so that the pressure on the rollers in the different streams will be equalized in case they vary in diameter. The mounting consists of a series 50 of coil springs 73 bearing against the inner surfaces of the discs and set in radial sockets 75 in a hub member fixed to the shaft 76. The discs are preferably toothed and are 55 confined against axial movement by end collars 77. In view of the movable mounting 60 of the shaft 76, tension on the sprocket chain

is maintained by movably mounting the sprocket wheel 88 between links 98 pivoted to a bracket 100 on the frame and by attaching a weight 102 to a bifurcated bar 104 hung on the shaft of the sprocket wheel. 70 The tube sections 64 are supported by plates 106 and 108 adjustably secured to brackets 110 and 112 by bolting them in slots in these last named numbers.

Referring to Figures 5 and 6, it will be 75 seen that the furnace 70 is divided horizontally and longitudinally and that the upper section is provided with eye bolts 116, by means of which the section may be lifted away from its corresponding half, through 80 the medium of a differential hoist or the like. This gives ready access to the lower lining in case it is desired to renew it or to the tubes 68 when they become burnt out. At the outlet end of the furnace are a series 85 of hoods 124, each having a cylindrical portion 126 sleeved over one of the tubes 68, said cylindrical portion opening into a chamber having flat parallel sides 128 to keep the rollers in alignment. The top of the chamber is curved at 130 to make room for the rollers to tilt preparatory to sliding down the inclined bottom 132 into a bath 134 of liquid. To allow ready inspection of the work each hood is provided with a peep hole 136 on a level with the furnace tube 68, the hole being closed by a hinged cover 138. When the rollers drop endwise the liquid is enabled to enter the core or inside as fast as it mounts on the outside and hence the rollers are quenched uniformly. The furnace is heated by liquid fuel supplied through a supply pipe 122 having at intervals suitable valves and burners extending towards the furnace. When the last rollers of a 100 batch have been conducted through the inclined tubes 62 to the feed discs, the lower ends of the tubes 62 can be uncoupled and turned to one side on the axis of the upper coupling, thus permitting a long rod to be 105 thrust through the furnace tubes to push out the remaining rollers.

Although the invention has been described by referring to a specific apparatus it should be understood that in its broader aspects the 110 invention is not necessarily limited to the specific structure selected for illustration.

I claim:

1. In apparatus for treating work pieces, in combination, a tube for guiding a stream of work pieces in end-to-end relation and having a slot, a feed disc projecting through said slot into contact with said work pieces, and means for rotating said disc to push the work pieces along in a stream, substantially as described.

2. In apparatus for treating work pieces, in combination, a tube for guiding a stream of work pieces in end-to-end relation and having a slot, a feed disc projecting through 130

said slot into contact with one of said work pieces, means for pressing said disc against said work piece, and means for rotating said disc to push the work pieces along in a stream, substantially as described.

3. In apparatus for treating work pieces, in combination, a tube for guiding a stream of work pieces in end-to-end relation and having opposite slots, feed discs projecting through said slots into contact with opposite sides of said work pieces, and means for rotating said discs to regulate the feed of the work pieces, substantially as described.

4. In apparatus for treating work pieces, in combination, a tube for guiding a stream of work pieces in end-to-end relation and having opposite slots, feed discs projecting through said slots into contact with opposite sides of said work pieces, means for yieldingly pressing one of the said discs towards the other to grip said work between them, and means for rotating said discs, substantially as described.

5. In apparatus for treating rollers, in combination, a series of tubes for guiding streams of rollers in end-to-end relation and having slots parallel to the axes of the tubes, a shaft, feed discs secured to said shaft and having yielding peripheries entering said slots for equalizing contact with rollers of different diameters, and means for rotating said shaft, substantially as described.

6. In apparatus for treating work pieces, in combination, a tube for guiding a stream of work pieces in end-to-end relation and having a slot, a feed disc projecting through said slot into contact with said work pieces, a pivoted support for said disc, means for swinging said pivoted support in a direction to press the disc against the work pieces, and means for rotating said disc; substantially as described.

7. In apparatus for treating work pieces, in combination, a hopper having an upwardly open channel in the bottom face to cause the work pieces to align by gravity, said channel having a longitudinal slot in its base, an endless chain supported below the hopper and a series of fingers having connection to the chain and arranged to project through the slot in the channel, and means for driving the chain to push the aligned pieces along in end-to-end relation; substantially as described.

55 8. In apparatus for treating work pieces, in combination, a hopper having an upwardly open channel in the bottom face to cause the work pieces to align by gravity, an endless chain supported below the hopper, a series of fingers having connection to the chain and arranged to successively traverse the channel to push the aligned pieces along in end-to-end relation, and means for guiding the fingers in a path at a slight angle to the length of the channel to cause the

fingers to successively leave the channel and transfer the pushing action to the following fingers; substantially as described.

9. In apparatus for treating work pieces, in combination, a hopper having upwardly open channels in the bottom face to cause the work pieces to align by gravity, an endless chain having a series of bars at right angles to the channels, a series of fingers attached to each bar and each projecting into one of the channels to push the aligned pieces along in end-to-end relation, means for guiding the bars, and means for driving the chain; substantially as described.

10. In apparatus for treating work pieces, in combination, a hopper having upwardly open channels in the bottom face to cause the work pieces to align by gravity, endless chains connected by a series of bars at right angles to the channels, a series of fingers attached to each bar and each projecting into one of the channels to push the aligned pieces along in end-to-end relation, means for guiding the bars and fingers at a slight angle to the length of the channel to cause the fingers to successively leave the channel and transfer the pushing action to the following fingers, and means to drive the chains; substantially as described.

11. In apparatus for treating rollers, in combination, a hopper having an upwardly open channel in the bottom face to cause the work pieces to align by gravity, a series of fingers projecting through the bottom of the hopper and arranged to enter each channel, driving means for moving the fingers lengthwise of the channel to pick up and feed a stream of work pieces in end-to-end relation, and a slip connection in said driving means; substantially as described.

12. In apparatus for treating work pieces, in combination, a guide for receiving a stream of work pieces in end-to-end relation and inclined to the horizontal to feed the work pieces by gravity, feed discs engaging the work pieces for regulating the speed of the work pieces through the guide and for controlling their subsequent traverse, and means for directing a supply of work pieces to the entrance end of the guide; substantially as described.

13. In apparatus for treating work pieces, in combination, a guide for receiving a stream of work pieces in end-to-end relation and inclined to the horizontal to feed the work pieces by gravity, driven rollers engaging the work pieces for regulating the speed of the work pieces through the guide, a hopper, means for raising the work pieces from the hopper and feeding them to the entrance end of the guide at a greater speed than they pass through the guide, and means for returning the excess pieces to the hopper; substantially as described.

14. In apparatus for treating work pieces,

in combination, a guide for receiving a stream of work pieces in end-to-end relation and inclined to the horizontal to feed the work pieces by gravity, means engaging the work-pieces for regulating the speed of the work pieces through the guide, a second guide comprising a tube extending to a point above the entrance end of the first guide,

and means for pushing the work pieces in a stream to the open end of the second guide 10 to drop them into the entrance end of the first guide; substantially as described.

In testimony whereof I hereunto affix my signature.

CONRAD KNOTH.
